UNITED STATES PATENT OFFICE.

CHARLES H. BUMP, OF BRANDON, VERMONT, ASSIGNOR TO THE NEWTON & THOMPSON MANUFACTURING COMPANY, OF SAME PLACE.

HANDLE-FINISHING MACHINE.

SPECIFICATION forming part of Letters Patent No. 594,825, dated November 30, 1897.

Application filed July 23, 1896. Serial No. 600,250. (No model.)

To all whom it may concern:

Be it known that I, CHARLES H. BUMP, of Brandon, in the county of Rutland and State of Vermont, have invented certain new and useful Improvements in Handle-Finishing Machines, of which the following is a specification.

This invention has relation to machines for finishing those handles which are usually employed in connection with wire bails for buckets, pails, &c., and has for its object to provide a machine for automatically rounding the ends of the handles and forming central longitudinal apertures through the same without any manual work save that required in feeding the blanks to the machine.

To these ends my invention consists of an improved machine having such parts and features as I shall now proceed to describe with particularity, and set forth in the appended claims.

Reference is to be had to the annexed drawings and to the letters marked thereon, forming a part of this specification, the same letters designating the same parts or features, as the case may be, wherever they occur.

Of the drawings, Figure 1 is a perspective view of one form of machine in which my invention is embodied. Fig. 2 is a plan view of the same. Fig. 3 is a transverse vertical section through the machine, showing the parts somewhat enlarged. Fig. 4 shows in detail one form of mechanism for imparting an intermittent movement to the carrier. Fig. 5 is a perspective view of the pawl employed with the device illustrated in Fig. 4. Fig. 6 shows in detail the cam for operating the stop mechanism.

In carrying out my invention, of which I have shown but one form in the accompanying drawings, I employ a frame having a platform *a* with legs or standards *b* for supporting the operative parts. In bearings *c*, formed with or secured to the end standards *b* of the frame, I mount a longitudinally-arranged main shaft *d*, to which power is imparted from a belt-wheel *e*, shaft *e'*, and gear-wheels *f* and *g*.

For receiving and supporting the handles while they are being dressed and finally prepared for use I employ a novel carrier, which

is shown at *h*. It consists of a disk or cylinder having in its periphery grooves *i*, which lie parallel to the axis thereof. These grooves are semicylindrical and are adapted to receive the handles from the feed-slide, from whence they are carried into position to be operated upon and are finally discharged.

The support and carrier *h* is mounted upon a short shaft *j*, journaled in bearings *k* upon the base or platform, and receives an intermittent motion from the main shaft *d* through the medium of the following devices: A rod *l*, depending from the base or platform, has pivoted to its lower end a bar *m*, which is connected by a link *n* with an arm *o*, loosely pivoted on the short shaft *j* and provided with a pawl or dog *p* on its free end. The end of the pawl is adapted to enter notches *q* in a disk *r*, formed integrally with the carrier *h* or rigidly secured to the shaft *j*. On the main shaft *d* is a cam *s*, which will depress the bar *m* once for each revolution and move the carrier forward one tooth. In order to return the bar *m* to its original position, I employ a spring *t*, connected with the outer free end of the bar. For insuring the stopping of the carrier at the exact point I employ a movable stop-slide *u*, sliding in guides *v* on the base or platform and adapted to engage the walls of the grooves in the carrier *h*. The slide is reciprocated by a lever *w*, pivoted in supports *x* and having on its free end a weight *y*. The lever is actuated by a cam *z* on the main shaft *d*.

The carrier-actuating device and the stopping devices are so timed that when the carrier is being moved forward the slide is withdrawn from engagement with it, and vice versa.

In connection with the movable carrier I employ a novel device for holding the handles securely in the peripheral grooves *i* while they are being operated upon. It consists of a segmental plate *a'* of iron, the segment being a portion of a circle concentric with the carrier. The under face of the plate *a'* is covered with a thick layer *b'* of elastic material, such as rubber or its equivalents, and the lower face of the rubber is covered with a piece of spring-steel *c'*, the whole forming an elastic or spring pad which adapts itself to any inequality of

the handles as they are being conveyed by the carrier, while at the same time it clamps the handles firmly in place while they are being operated upon. The segmental pad is supported by a vertical rod d^2 , depending from braces or standards e^2 , bolted to the base or platform a . The upper end of the rod d^2 is screw-threaded and is provided with a nut f^2 , so that the pad may be adjusted vertically as desired.

Before feeding the handles to the machine they are first turned and cut into the shape of short cylinders, and they are then ready to have their ends rounded and to have a longitudinal through-slot bored in them.

I shall now proceed to describe the tools and devices for rounding the ends and forming the slots or apertures just referred to.

g^2 indicates two rotary spindles, which are mounted in bearings h^2 on the platform. The ends of the spindles are provided with bits and cutters i^2 for first rounding the ends of the handles and forming short apertures therein.

j^2 indicates similar spindles, which are provided on the ends with long bits or boring-tools k^2 . The handles are first acted upon by cutter-heads, which center them and the bits boring short through-holes in them. The handle is then transferred by the carrier into the line of the bits k^2 to be acted upon by them. The spindles are rotated by belt-wheels l^2 , rigidly mounted on them; but they also have a longitudinal movement, which is effected as follows: m^2 are saddles, which are secured to the spindles j^2 , between collars n^2 , the saddles traveling back and forward with the spindles j^2 and having more or less of a sliding movement relative to the spindles g^2 , between the collars o^2 thereon. For sliding the saddles back and forth I employ at each end of the machine a lever p^2 , mounted in supports q^2 and having on its lower end a roller r^2 , bearing against a cam s^2 , mounted upon the main shaft d . When the said shaft d is rotated, the lever p^2 will force the saddle m^2 forward. The spindle j^2 will be forced steadily forward, while the spindle g^2 will not be actuated until the saddles come into engagement with the inner one of the two collars o^2 . The levers p^2 are returned to their original positions by springs t^2 , of which each has one end secured to the end of the levers p^2 and the other end to a rod u^2 , projecting from the standard.

v^2 is a feed-slide on which the roughly-finished handles are placed to be fed to the carrier.

w^2 is a wire spring secured to the feed-slide for holding the handles in place.

To assist the stop-slide in preventing the carrier from moving while the handles are being acted upon, I employ an additional device consisting of a rod a^3 , secured at one end to the levers p^2 and having at its other end a finger b^3 , adapted to be thrust into one of a series of holes c^3 in the carrier.

A number of roughly-finished handles are

placed upon the feed-slide. As the carrier is intermittently actuated the handles one by one will fit into one of the grooves in the carrier and will in due time be carried into the vertical lines of the spindles g^2 . The rotation of the main shaft d will, through the cam s^2 and lever p^2 , force the spindles g^2 forward, so that the cutters will act upon the end of the handles and around them, also forming in the ends of the handles short apertures. The carrier being again actuated, the handles will be carried forward and ultimately arrive in the lines of the spindles j^2 . The bits k^2 require that the spindles j^2 should be moved forward for a considerable distance in order to bore through apertures, while the cutters i^2 need to be fed forward but a short distance, and hence the saddles m^2 are arranged so as to have a sliding relationship relatively to the spindle g^2 and to move them forward during but a portion of their movement. After the handles have been acted upon the continued rotation of the carrier will carry the finished handles around until they are engaged by the spring a^4 , which will free them from the carrier. I so time the parts that one of the bits k^2 will move slightly in advance of the other one in order that they will not strike against each other in forming the through-slot.

Having thus explained the nature of the invention and described a way of constructing and using the same, though without attempting to set forth all of the forms in which it may be made or all of the modes of its use, it is declared that what is claimed is—

1. In a machine for finishing handles, a rotary carrier provided with peripheral receptacles for the blanks, in combination with a segmental pad arranged to hold the blanks in the said receptacles, the said pad consisting of a layer of rubber or equivalent material having a metallic frame or backing and a flexible metallic bearing-face the said backing rubber layer and metallic face being secured together and fitting upon each other throughout the length of the pad so as to form one solid integral device, substantially as set forth.

2. A rotary carrier-disk h having grooves i in its periphery, in combination with a notched disk r turning with the said carrier, a pawl engaging the said disk r to turn the same, a cam s , bar m , link n and arm o for operating said pawl from the driving-shaft, a retracting-spring t connected to said bar, a stop-slide u arranged to engage the grooves i of the carrier, a weighted lever w , operating the said slide, and the main shaft and its cam z for actuating the said lever substantially as set forth.

3. In combination with a rotary blank-carrier having peripheral grooves or recesses and holes or recesses in its side, a pair of stops one engaging with said grooves the other with said holes, levers actuating the said stops and a rotary shaft provided with cams whereby

said levers are independently actuated substantially as set forth.

4. In combination with a tool-blank carrier, a pair of cutter-spindles arranged to act on the blanks in said carrier, a saddle attached to one of the said spindles and entering between collars on the other arranged to allow unequal longitudinal motion of the two spindles, a lever attached to the said saddle, a shaft and cam for actuating the said lever and a rod attached to the said lever and adapt-

ed to enter a hole or recess of the carrier for holding the latter without motion substantially as set forth.

In testimony whereof I have signed my 15 name to this specification, in the presence of two subscribing witnesses, this 18th day of January, A. D. 1896.

CHARLES H. BUMP.
